(57) **CLAIM**

The ornamental design for a shaker lid, as shown and described.

DESCRIPTION

FIG. 1 is a front view of the shaker lid of the present design, the rear view and side views being identical thereto;
FIG. 2 is a top view of the shaker lid of the present design;
FIG. 3 is a bottom view of the shaker lid of the present design;

FIG. 4 is a front perspective view of the shaker lid of the present design;

FIG. 5 is a bottom perspective view of the shaker lid of the present design;

FIG. 6 is a front view of the shaker lid of the present design mounted on a shaker bottle, the rear view and side views being identical thereto; and,

FIG. 7 is a front perspective view of the shaker lid of the present design mounted on a shaker bottle.

The broken lines showing a shaker bottle in FIGS. 6 and 7 are for the purpose of illustrating environmental structure and form no part of the claim.

1 Claim, 7 Drawing Sheets
